UNITED STATES PATENT OFFICE.

ELMER L. SMITH AND HORACE J. PAYNTER, OF SPRINGFIELD, MASSACHUSETTS, ASSIGNEES TO PACKAGE MACHINERY COMPANY, OF SPRINGFIELD, MASSACHUSETTS, A CORPORATION OF MASSACHUSETTS.

YEAST-CAKE FORMING AND WRAPPING MACHINE.

Application filed August 31, 1921. Serial No. 497,311.

The present invention relates to improvements in wrapping machines and associated mechanism, and has for its object more particularly the provision of a combined mechanism for forming a plastic material like yeast into cakes and wrapping the same.

In furtherance of this object, mechanism is provided to continuously supply to the wrapping mechanism, cakes or articles of uniform size and length and to wrap the articles thus supplied in a manner to avoid mutilation of the articles or the wrapper. The wrapping of yeast cakes is preferably performed with a waterproof material such as foil, and in consequence, a further object of the invention is the provision of wrapping devices as will properly handle a delicate wrapper such as foil.

It is desirable in a machine of this character to insure the continuous supply of uniformly shaped cakes or articles for the rapid and efficient operation of the machine and for this purpose preliminary forming means are provided to receive the material in slabs of any length supplied and to divide said slabs into blocks of material which will contain a multiple of equal length units or cakes. Unit cutting mechanism is provided to cut the blocks into the unit or single articles together with means for transferring the same to the wrapping mechanism. Furthermore, the feeding and wrapping of a material like yeast requires special treatment to prevent crumbling or destruction of the cakes, and the present mechanism is designed particularly with the object in view of avoiding unnecessary stresses upon the material such as friction or pressure would create.

Other and further objects of the invention will appear from the following description taken in connection with the accompanying drawings, and the scope of the invention will be defined in the appended claims.

In the drawings which show a preferred embodiment of the invention,

Fig. 1 is a side elevational view of the article-forming mechanism;

Fig. 2 is a plan view of the same;

Fig. 3 is an enlarged sectional view on the line III—III of Fig. 2;

Fig. 4 is a similar sectional view on the line IV—IV of Fig. 2;

Fig. 5 is a fragmentary view on the line

IV—IV of Fig. 2 with the parts in another position;

55

Fig. 6 is an enlarged plan view taken on the VI—VI of Fig. 1 showing certain of the parts in section;

Figs. 7, 8, 9, 10, and 10^a are fragmentary elevational views on an enlarged scale of the 60 block, cutting, conveying, and wrapping mechanism;

Fig. 11 is a view taken on the line XI—XI of Fig. 8;

Fig. 12 is a sectional view taken on the 65 line XII—XII of Fig. 8;

Fig. 13 is a small scale diagrammatic view of the block advancing means;

Fig. 14 is a side elevational view of the 70 wrapping mechanism to which the article-forming mechanism is connected;

Fig. 15 is a plan view of the same with the upper wrapper-feeding mechanism removed;

Fig. 16 is a sectional elevational view taken on the line XVI—XVI of Fig. 15;

75

Figs. 17, 18, 19, 20 and 21 are perspective views showing the wrapper and articles in the various steps of the wrapping operation.

The invention will first be described briefly, to facilitate a clear preliminary understanding thereof. It consists in general of the forming mechanism shown in Figs. 1 and 2 that is adapted and arranged to advance a block of material to a cutting device that successively severs or cuts from the block of material units of equal length which for convenience may hereinafter be termed "articles." The material supplied to the forming mechanism may be the usual slab of plastic composition such as a yeast which may vary in length but which is preferably rectangular in cross section so that yeast cakes of regular form and size may be cut therefrom by a cutting device operating at right angles to the axis of the slab or block.

80

The articles formed by being cut or severed from the block may be conveyed by the conveying means or grippers to a table or machine for subsequent operations, but for the purpose of disclosing one practical advantageous use of the device it is shown in connection with a wrapping machine to which the formed articles are conveyed and in which it is enclosed in a wrapper by successive steps, as shown in Figs. 17 to 21.

85

100

A base 1 (see Figs. 1 and 14) is provided

105

and may be supported by the usual standards 2. A bracket 3 is fixed to an end of the base and is provided with bearings 4, 5 and 6. A stud 7 fixed to the bracket 3 supports a sliding carriage 8. A shaft 8' rotatably mounted in the carriage 8 has fixed to its forward end a belt-driving pulley 9 and to the rear end thereof is secured a worm-gear 10 that is in meshing engagement with 10 and driven by a worm 11, fixed to the end of a rotating shaft 29. A rod 12 fixed to the carriage 8 is reciprocably carried in a suitable bearing of the bracket 3 and serves to retain the said carriage in its proper position 15 on the support 7, as shown in Fig. 1. A shelf 13 is supported by a stud 14 fixed to the bracket 3 and extends forwardly thereof to a support 15 carried by a bracket 16 (see Fig. 14). Plates 17 fixed to both sides and 20 at the forward end of the shelf 13 carry there-between an idler-pulley 18. An endless conveying belt 19 is carried by the pulleys 9 and 18 and as will be seen is supported on its upper run by the shelf 13. A tension spring 20 suitably connected to the rod 12 and bracket 3 tends to pull the carriage 8 rearwardly upon its support and functions to keep the conveying belt 19 taut.

A shaft 25 is rotatably supported in the 30 bearing 6 of the bracket 3 and serves as a source of power for driving the forming mechanism and the conveyor belt. This shaft 25 may be driven by a pulley in the usual manner, but is here shown as being operably connected to driving mechanism of the wrapping machine with which the device is used. A gear 26 carried on the end of the shaft 25 is in meshing engagement with an idler 27 carried on a suitable stud 35 of the bracket 3 which idler engages with a driven gear 28 fixed to the shaft 29. The shaft 29 is rotatably mounted in the bearing 5 of the bracket 3 and at one portion has the worm 11 for driving the belt 19 and at 40 another portion of its length adjacent the gear 28 is provided with a screw-thread 30 that is adapted to drive the forming mechanism, as will later appear.

A guide rail 32 disposed parallel to the 50 screw 30 is located thereunder and is supported by the bracket 3 at one end and by a bracket 16 at its opposite end. A notch 33 is provided in the guide rail and serves to release or let off the forming mechanism 55 from a further advancing movement, in a manner later to be described.

The block forming mechanism for cutting the slab of material into predetermined 60 lengths will now be described with reference particularly to Figs. 1 to 6, inc. A sleeve member 36 is mounted for reciprocating movement on the driving screw 30 and has a bifurcated or forked portion 36' that engages opposite sides of the guide rail 32 65 to hold the sleeve member from rotation and

to allow its reciprocating movement. A nut member 37 is slidably mounted at one side of the sleeve member 36 and is provided with suitable worm teeth 37' for engaging with the thread 30' of the screw 30. An offset 70 projection 38 carried by the nut 37, as best shown in Fig. 6, serves as an abutment against which a compression spring 39 of the member 36 acts. This spring 39 tends to move the nut 37 from engagement with the screw 30 when released by the forming cutter now to be described.

A cutter-frame 40 has bearing members 41 rotatably mounted on the screw part 30 of the shaft 29 and the inner faces of the 80 bearings 41 abut opposite ends of the sleeve member 36, whereby the frame 40 may be reciprocated along the screw by the member 36 and may be swung about the screw 30 for the cutting operation. A downwardly-projecting arm 42 carried by the rear bearing member 41 is provided with a sliding latch 43. A compression spring 44 carried in a recess of the projection 42 bears against the latch to normally retain it in its latching position shown in Figs 1 and 3. A projecting pin 46 carried by the latch 43 is preferably arranged to interfit a suitable slot in the latch carrier which serves as a stop to limit the outward movement of the latch. The 95 pin 46 may also be raised by hand when desired to release the latch.

A tension spring 47 is connected to a lug 48 of the former 40 and to a downwardly-projecting spring-carrier 49 secured to the reciprocable sleeve member 36, and functions to automatically swing the former 40 to its non-cutting position, shown in Fig. 5, when the latch is released by the notch 33 of the guide rail 32. The longitudinal side of the 105 former 40 is arranged in the form of a straight wall or guide 50 against which a slab of material may be placed, when the former is in its lowered or operating position, and functions to aline the block or slab 110 of material with respect to the belt and the longitudinal axis of the machine. A transverse flange 51 of the former 40 has fixed thereto a vertically disposed cutting blade 52, which when in its lowered position adjacent the belt 19 serves as an abutment against the rear side of which the forward end of a slab advancing on the belt to be cut may be located. An operating grip handle 45 is fixed to the oscillating former 120 40 to facilitate the manual operation of the device, to its cutting position.

A cam-plate 53' is adjustably secured to the former 40 by means of a wedge member 54 and an adjusting screw 55. This cam 53' is preferably arranged to move the nut 37 to an operating engagement with the screw 30 when the forming cutter is moved from its non-cutting position in Fig. 5 to its cutting position shown in Figs. 3 and 4. The adjusting 130

means allows the cam to be moved toward the screw 30 to compensate for wear or looseness that may develop in the interfitting nut 37 and threads 30' of the screw.

5 As will be observed, the swinging member 40 carrying the cutter 52 is fed along by the screw until the latch 43 slips through the notch 33 in the guide rail 32. At this time the cutter will swing to the position shown 10 in Fig. 5. In this position the nut 37 is disengaged from the screw threads so that the member 40 may be moved rearwardly to locate the knife 52 at the rear of a block of yeast on the belt. The pitch or lead of the 15 thread of the screw 30 and the arrangement of the parts is preferably such that the member 40 may be swung downwardly only at such times as will locate the cutter 52 at distances from the unit cutting mechanism 20 which will be equal to multiples of the width of the units to be cut. With this arrangement, as the cutter 52 is lowered it will cut off the end of a block on the belt so that the block will be in length equal to multiples of 25 the units to be cut therefrom. The cutter 52 has a further advantageous feature in that when in lowered position it will back up a block of yeast on the belt and while it travels at the same lineal speed as said belt it 30 will tend to feed the block forwardly so that the block will not slip on the belt; that is to say, the cutter cooperates with the belt and acts as a pusher to feed the block forwardly to the unit cutting mechanism.

35 The unit cutting mechanism for cutting units of equal length from the block of material and thus successively form articles will now be described with reference to Figs. 7, 8, 9, 15, and 16. A cutter frame 60, as best 40 shown in Fig. 16, carries in its depending spaced portions 61 a cutting member C of wire or the like, and an adjusting reel screw 63 is provided to tension the cutting member. The cutter frame 60 is adjustably secured, as at 64, to a bell crank lever 65 that is fixed to the end of a shaft 66. A downwardly-depending arm 67 of the lever 65 has a cam roll 68 at its lower end that is in engagement with the periphery of a cam 67' fixed to 45 the operating shaft 25. A spring 60' is connected between the cutter frame 60 and the main frame 31 to hold the cam roll in contact with its cam 67'. The shaft 66 carrying the lever 65 is rotatably and reciprocably mounted in a suitable bearing 68' fixed to the frame 31. This mechanism is adapted and arranged to swing the cutting frame toward the block of material carried by the belt in a timed relation with other units of the machine to cut from the block articles of equal 50 length, and means are provided to reciprocate the cutter so as to move the same forwardly in uniform relation with the belt 13 during the cutting operation, whereby articles are cut in equal length perpendicularly.

to the belt and to the axis of the advancing block.

The means for imparting the reciprocating movement to the cutting frame comprises a cam 69 fixed to a continuously-operating 70 shaft 70 of the machine against which one end of the oscillating shaft 66 is adapted to bear by means of the tension spring 71 connected to the lever 65 and bearing 68'. This cam 69 is preferably of such shape as to allow the spring 71 to carry the cutting frame forwardly at an equal rate of speed with the block of material and belt 13 during the cutting operation and to return the frame 80 rearwardly the proper distance for a new cut after each cutting operation. The cam 67' has a suitably formed wave like track at its periphery to keep in contact with the roll 68 of lever 65 during the reciprocating movement of shaft 66.

85 Means are provided to engage opposite sides of the end of the block, or article being cut therefrom during the cutting operation and to transfer the formed article from the belt to the wrapping mechanism hereinafter described. This mechanism is arranged to advance with the article in unison with the traveling belt during the cutting operation and functions to hold the article being formed by the cutter C during its operation 90 and prevents the displacement or disalignment thereof with respect to other units of the machine, and is as follows:

95 Gripping members 76 fixed upon vertically disposed swinging shafts 77 are provided with article-engaging surfaces 78 best shown in Fig. 8 and are preferably of a shape and size as to lie flush with the vertical forward edges, and the upper and lower edges at each side of the article for the purpose later to be described. The shafts 77 carrying the grippers 78 are provided at their lower ends with gear segments 79, whereby a uniform relative movement of the grippers toward or away from the article is assured, and a 100 tension spring 80 connects the arms to force them toward one another for the gripping action.

105 The reciprocating travel of the grippers so as to advance with the article is accomplished by the mechanism shown more clearly in Figs. 14, 15, and 16. A fore and aft slide 86 is reciprocably mounted by a dove-tail 87 at one side thereof to the bracket 16, and the gripper shafts 77, before mentioned, are pivotally mounted in suitable bearings carried in said slide 86. A connecting rod 88 connects the slide 86 to the operating lever 89 that is pivoted to the bed 1 at 90. A cam 91 fixed to and driven by the shaft 93 is provided with a suitable cam groove 92 that receives a cam roll 94 of the lever 89, whereby the lever is swung to reciprocate the slide in its proper timed relation.

110 The grippers 78 are clamped upon the arti- 130

cle during the advancing and cutting operation but are caused to release the article after the article has been conveyed by them to the wrapping mechanism, also they are held in an 5 open position during their return movement to their article-engaging position. This is accomplished by a transversely reciprocating slide 81 carried in the bracket 16 to the forward end of which is secured a longitudinally 10 extending U-shaped track or guide 82. An arm 83 carried by one of the gear segments 79 has a roll in operable engagement with the guide 82, whereby a reciprocation of the slide 81 and guide 82 swings the arm and results in 15 an opening movement of the grippers. A cam 84 fixed upon the operating shaft 25 is provided with a suitable cam groove (not shown) in which is carried a cam roll 85 of the slide 81 (see Fig. 15). This cam is preferably 20 adapted to reciprocate the slide 81 and guide 82 in a timed relation with the cutter and other units of the machine, whereby the grippers are allowed to close upon the article by the action of the spring 80 and are opened by 25 the lever 83.

The wrapping mechanism will now be described. A shaft 93 is carried by the frames 31 and 32 and is driven by means of a gear 93' fixed thereto which is in meshing engagement 30 with a driving pinion 94 of the main shaft 95. A gear 97 carried by the shaft 93 is in meshing engagement with a gear 98 on the previously referred to shaft 70, whereby the said shaft 70 receives a continuous motion. A Geneva driver 99 (see Fig. 14) is carried by the shaft 70 and actuates a Geneva wheel 99' fixed to a hollow shaft 100 for delivering to the shaft 100 an intermittent motion in the usual manner. A tumble-box or pocketed 35 wheel 101 is fixed to the hollow shaft 100 and is provided at its periphery with recesses or pockets 101' which are open at the ends whereby said pockets are adapted to receive an article and a wrapper folded about three sides of 40 said article.

Wrappers for the article are preferably cut from a continuous strip of wrapping material by mechanism now to be described. A frame 102 supports on its upper end an arbor 50 103 on which may be mounted the usual roll W of wrapping material. Feed-rolls 104 and 105 are rotatably carried by the frame 102 and are adapted to unwind a proper length of wrapping material during each cycle of 55 operation of the machine. A sprocket 106 is fixed to the shaft of the roll 104 and is driven by means of the chain 107 that receives a continuous motion from the sprocket 108 of the shaft 70. A rod 109 carried by the frame 60 103 guides a weighted roller 110 under which the web of wrapping material is fed, which roller serves in the usual way to take up and tension the web of material. A supporting guide plate 111, as shown in Fig. 14, is provided over which the wrapping material is

fed. Shears 112 are pivotally supported by a lug 113 of the frame 31 and are operated to cut a proper length of wrapping material from the strip as it is fed therewith. The shears 112 are operated by a link 113', lever 70 114 pivoted at 114' and cam 115 fixed to the shaft 25.

Wrapper nippers to position and deliver the severed wrappers to their position in the path of an article and between the same and the pocket 101' of the wheel 100 will now be described with reference to Figs. 14, 15, and 16. A nipper frame 121 having a rigid jaw 122 is fixed to the upper end of a reciprocable slide 123. A movable jaw 124 having a resilient wrapper-gripping plate 125 is pivotally connected by a link 126 to the link 127 which is preferably provided with a roll as shown. The links are arranged in the form of a toggle, whereby a swinging movement of the link 127 in one direction will hold the movable member 125 against the rigid member 122 while a movement in the opposite direction will cause the members to separate to release a wrapper held therebetween. 90

The slide 123 carrying the nipper is arranged to move from an upper position where an end of the wrapping material is gripped by the nippers to a lower position whereby a length of material for one wrapper has been 95 advanced to a position adjacent a pocket 101' of the wheel 101. The slide 123 is slidably guided for its vertical movement in spaced parallel guides 129 carried on a rocking frame 128 the latter being pivoted freely on 100 shaft 136. A spring 142 is connected between said frame 128 and the main frame tending to rock said frame to the left viewing Fig. 16. A tail portion 200 at the lower end of said frame 128 is forked over a rod 201 having an 105 adjustable stop nut 202 at its outer end to limit the rocking movement of said frame under the tendency of said spring. An operating lever 130 pivoted at 130' is connected by a link 131 to the slide 123 and has a cam roll 110 132 engaging a cam groove (not shown) of the cam 133 whereby an oscillation of the lever 130 will reciprocate the slide 123 vertically in a timed relation with the other units of the machine. 115

A vertical channel member 134 is fixed to a rocking lever 135 pivoted to the frame 16 at 136 and said channel member serves to engage the cam roll of the nipper link 127 during its vertical travel, and as the lever 135 120 and channel 134 are oscillated moves the link 127 to open or close the nipper jaws 122 and 125. The lever 135 is oscillated by a cam fork 137 pivotally connected thereto at 138. The cam fork 137 is in sliding engagement with 125 a block 139 loosely mounted upon the shaft 25 and has a roll 140 in operable engagement with a cam groove 141 in one face of the cam 133. The lever 135 carries a pin 203 adapted to abut an adjustable stud screw 204 carried 130

on the frame 128 so that the swinging movement of said lever 135 to the right viewing Fig. 16 will also swing the rocking frame 128 against the tension of the spring 142. By the arrangement above described the nippers 122, 125 are caused to travel vertically downward when in closed position to carry the wrapper *w* in front of the article to be wrapped. The parts of the machine are so timed that the article grippers 78 are in the act of carrying the article against the wrapper and into the pocket of the wrapping wheel before the wrapper nippers again reach their upper position. Therefore, the nippers 122, 125 and 15 nipper frame 123 are carried outwardly during the upward travel thereof so as to avoid interference with the grippers 78, which is effected by the outward swing of the frame 128 in which the nipper frame is slidably mounted. It will be observed that the swinging lever 135 which carries the channel 134 to open the nippers likewise effects the swinging of the frame 128 after said nippers are opened.

Each article *a* cut by the unit cutting mechanism as hereinbefore described is successively carried by the grippers 78 from the belt 19 against a wrapper and into a pocket 101' of the wrapping wheel which operation causes the wrapper to be folded about the three 20 sides of the article *a* as shown in Figs. 8, 9 and 12. Inasmuch as the forward, the upper and the lower edges of the grippers 78 lie flush with the adjacent edges of the article the wrapper is in effect engaged and folded by the metal surfaces of the grippers 78 co-acting with the walls of the pocket 101', and thus avoids the chance of mutilating the soft plastic material of the article during this part of the folding operation.

40 Wrapper clamps 144 (see Fig. 14) located on both sides of the wrapping wheel 101 are supported upon the rods 145 fixed to an oscillating shaft 146. A lever 147 fixed to the shaft 146 is moved in an upward position by the tension spring 148 whereby a severed wrapper is held in its position between the clamps 144 and plate 149 after the same has been moved therebetween after the cutting operation. The clamps 144 are also arranged to yieldingly press the positioned wrapper against the forward edges of the grippers 78 in the manner shown in Figs. 8, 9 and 12 when the article is being transferred with its wrapper by said grippers into the folding pocket 101'. A cam 150 fixed on the end of the shaft 93 engages a roll 151 upon the end of the lever 147, and is preferably so formed as to cause the clamps to be swung away from the article and wrapper when they have been delivered into the wrapping wheel.

60 After the article *a* and wrapper *w* have been transferred into the pocket 101' of the wrapping wheel a side folder 153 is operated to fold down one flap *b* of the wrapper as shown in Fig. 10. This side folder 153 is

fixed to a shaft 154' pivoted in the outer end of an oscillating lever 154 fixed to a shaft 155 that is rotatably carried in the hollow shaft 100. The shaft 155 is oscillated to operate the folder in its proper timed relation by a lever 156 fixed thereto that has a roll engaging with a cam groove (not shown) in a face of the gear 98 (see Fig. 15). The movement of the folding lever 153 in folding or wiping down the flap *b* of the wrapper is controlled by special connections so that the folding edge 153' of said lever 153 will tend to describe a convexly curved path as indicated diagrammatically in Fig. 10^a and thus clear the upper corner of the article *a* in the pocket 101' and press by yielding contact the wrapper down upon the article. The wrapping wheel in its further advance provides a clearance for the return of said folder 153 to its initial position for folding the next wrapper. These special connections comprise a link 300 pivoted on a stud 301 fixed to the main frame. A rod 302 has a pin and slot connection at one end with the link 300 and is firmly fixed at its other end to shaft 154'. A spring 303 connects folding lever 153 to the lever 154 and acts to yieldingly press the folder against the wrapper and article during the folding operation.

Upon completion of the folding action of folder 153, the wrapping wheel 100 is given a partial rotation to bring a succeeding pocket 101' in position for receiving the next article and wrapper and during this partial revolution of the wheel 100 a stationary folder 152 acts to fold the flap *d* of the wrapper down upon the side of the article *a* so as to overlap the flap *b* (see Fig. 10). The folding blade 152 is preferably formed as a forward extension of a brush frame 152' which is fixed to the frame of the machine and is disposed circumferentially of the wrapping wheel 100 as shown in Fig. 14.

When the wrapping wheel has been intermittently operated to bring its pocket and the partially wrapped article *a* to the lower side of the wheel end tucks *e* of the wrapper at each end of the article are effected as shown in Fig. 20. These end tucks are made by vertically moving end folders 160 one at each side of the wrapping wheel which are carried on rods 161 fixed to an oscillating shaft 163 (see Fig. 14). The shaft 163 is oscillated in proper timed relation by an eccentric 164 mounted on the shaft 93, which eccentric has an arm 164' pivotally connected to an arm 165 fixed to the shaft 93.

Immediately after the end tucks *e* are effected, and before the end folders are completely withdrawn, the first corner tucks *f* (see Fig. 21) are made at each end of the article by movable tucker blades 157 (see Fig. 14). The tucker blades 157 are mounted one at each side of the wrapping wheel, upon arms 158 which are in turn carried

upon a compound reciprocating and oscillating frame 159 operated from an eccentric 159' mounted on the shaft 93. The frame 159 is formed with a slotted bearing 5 158' to travel on a block 350 pivoted on the main frame at 351 whereby said frame 159 receives from its eccentric 159' a compound oscillatory and reciprocatory movement. This movement of the frame 159 carries the 10 tucker blades 157 in an elliptical path across the ends of the article to withdraw the same downwardly clear of the wrapping wheel at the finish of said folding operation.

Mounted at each side of the wrapping 15 wheel in a fixed position on the frame are slotted folding horns 167 having corner tuckers 167' extending therefrom to a point adjacent the end folders 160 (see Fig. 14). As the wrapping wheel carries the article *a* from 20 its lowermost position and after the tucks *e* and *f* have been effected, and preferably before the tucker blades 157 have left contact with the ends of the article, the corners *g* (see Fig. 21) of the wrapper are engaged by the corner tuckers 167' and tucked against each end of the article. The continued travel of the article *a* and its wrapper eventually brings last remaining flaps *i* of the wrapper into the slots 168 of the folding horns which gradually fold down said flaps *i* upon the ends of the article. The wrapper is thus completely folded about the article and in the further travel of the wrapper wheel, labels or other devices may be 35 applied to the wrapped article by any suitable mechanism (not shown).

When the article reaches the uppermost 40 position on the wheel, it registers with an ejection chute 181 into which it is ejected transversely from the wrapping wheel on to a table 182 by an ejector 175 reciprocally guided on a support 176. The ejector 175 is operated from a link 180 connected to a lever 179 pivoted at 179' and operated by its cam 45 roll 250 working in a groove of the cam 179 fixed to the shaft 25.

A brush 166 mounted in the frame 152' is disposed circumferentially of the wrapping wheel and, as shown, extends preferably from 50 a point adjacent the position of the receiving pocket to a point adjacent the position of the ejecting pocket. This brush functions to hold the articles being wrapped against displacement in their respective pockets during a rotation of the wheels without exerting undue pressure thereon.

Operation.—The operation of the machine and the function of its various parts may be 60 briefly described as follows. It will be understood that the shaft 25 is adapted to drive the forming mechanism and the conveyor belt 19 in synchronism with the unit cutting mechanism and wrapping mechanism of the machine. The immediate driving 65 means or screw 30 of the forming mechanism

is adapted to advance the forming cutter 52 at the same rate of speed as the conveyor belt 19 travels in advancing a block of material toward said unit cutting mechanism, and the forming cutter blade 52 acts 70 as a positively acting pusher for the block of material to insure proper travel of the same. The belt 19 serves as a moving support for the material as it is advanced by the pusher or cutter blade 52 and might be 75 dispensed with in the case of less plastic material than yeast which could perhaps be pushed along a stationary table without disintegration by friction.

Assuming the machine is primed for starting operation by a proper length of block of material placed on the belt 19 in front of the forming cutter 52 for being cut into units of equal length by the unit cutting mechanism, the operation of the machine will continuously advance said block of material toward the unit cutting mechanism. At any time during said advancing movement of the block, a new slab of material of unmeasured length may be placed by the operator 80 on the conveyor belt at the rear of the cutting blade 52 and the forward end of said slab should be abutted against the rear side of said blade 52 and the longitudinal side of said slab abutted against the side wall 50 95 of said forming mechanism to properly locate and align the slab on the belt.

When the forming cutter 52 has advanced far enough to bring the latch 43 to the notch 33 in the guide rail 32, the cutter frame 40 100 will be swung upwardly by the spring 47 to the position shown in Fig. 5, and the nut 37 will be automatically disengaged from the driving screw 30. The forming cutter and its frame 40 may then be slid to the rear by 105 grasping the handle 45 preparatory to the cutting of a new block from the advancing slab on the belt.

The forming cutter 52 cannot be swung 110 downwardly for cutting the new block until the nut 37 is in position for reengaging the threads of the screw 30 due to the coaction of the cam 53 with said nut 37. The pitch of the screw 30 is such that the nut 37 is engageable therewith only when the forming 115 cutter is at a distance from the cutting plane of the unit cutting mechanism equal to a multiple of the unit lengths of the articles to be cut thereby insuring that each block of material fed to the unit cutting mechanism 120 will be cut evenly into units or articles for transfer to the wrapping mechanism. In this manner the operator can keep the machine supplied for continuous operation and any remnants or partial units of material may be 125 removed from the belt at the rear of the forming cutter 52 without stopping the machine.

The unit cutting mechanism is arranged to cut the articles from a continuously advancing block, and in order to cut the articles 130

perpendicularly to the axis thereof, the cutting wire C and its frame is caused to advance uniformly with the block during the cutting operation by the mechanism described. As shown in Figs. 7, 8 and 9, the cutting wire C during the cutting operation, travels in the path *c* to *c'*. During this cutting operation, the grippers 78 are clamped with yielding pressure upon the ends of the unit being cut to prevent its displacement.

As soon as the cutting wire C completely severs the unit or article, it is caused to advance forwardly and upwardly from the points *c'* and *c''*, see Fig. 9, and in this forward movement, the cutting wire C advances slightly faster than advancing article *a* so as to clear the forward side thereof. Upon reaching the point *c''*, the cutting wire continues its movement and travels backwardly to its initial position *c* ready for a new cutting operation. After the cake or article is severed by the cutting wire C the grippers 78 carry it forward faster than the travel of the cutting wire C to clear the same.

Previous to the gripping and transfer of the article *a* by the grippers 78 a wrapper *w* has been positioned in front of a pocket 101' of the wrapping wheel by the nippers 122, 125 of the wrapper advancing means as previously described, and the wrapper *w* is securely held in this position by being clamped between the plate 149 and yielding clamps 144 ready for engagement by the forward edges of the grippers 78 as described. The grippers 78 carry the article with its wrapper into the pocket 101' of the wrapping wheel as shown in Fig. 9, said grippers acting to push back the yielding clamps 144 in the manner shown. During this transfer of the article by the grippers into the pocket, the wrapper *w* is folded by the pocket and the engaging edges of the grippers so as to lie about three sides of the article.

After the article and wrapper are received in the pocket, the clamps 144 are swung back by the mechanism described and the wrapping wheel 100 begins its step by step rotation to carry the article past the various folding devices for completely wrapping the article as has been described. The fully wrapped article is finally ejected from the top of the wrapping wheel by the ejector 175 on to the table 182.

While we have shown and described a preferred embodiment of the invention in the form of particular mechanism designed to carry out the purposes and objects of the invention, yet it should be understood that the invention is not limited to the details shown, but is defined as to scope in the appended claims.

What we claim is:

1. In a machine of the class described, unit cutting mechanism operated to cut material advanced thereto into units of equal length,

block forming mechanism arranged to form the material so advanced into a block equal in length to a multiple of the units to be cut, and means for driving said block forming mechanism to advance with said material toward said unit cutting mechanism.

2. In a machine of the class described, unit cutting mechanism operated to cut material advanced thereto into units of equal length, block forming mechanism arranged to form the material so advanced into a block equal in length to a multiple of the units to be cut, means for driving said block forming mechanism to advance with said material toward said unit cutting mechanism, and means for automatically releasing said block forming mechanism from said driving means when advanced to a point adjacent said unit cutting mechanism.

3. In a machine of the class described, unit cutting mechanism operated to cut material advanced thereto into units of equal length, an underlying support for said material traveling with the same to said unit cutting mechanism, and block forming mechanism arranged to form the material so advanced into a block equal in length to a multiple of the units to be cut.

4. In a machine of the class described, unit cutting mechanism operated to cut material advanced thereto into units of equal length, a continuously moving support for said material traveling with the same to said unit cutting mechanism, block forming mechanism arranged to form the material so advanced into a block equal in length to a multiple of the units to be cut, and means for driving said block forming mechanism to advance with said material toward said unit cutting mechanism at the same rate of speed as said traveling support.

5. In a machine of the class described, unit cutting mechanism operated to cut material advanced thereto into units of equal length, block forming mechanism arranged to form said material so advanced into a block equal in length to a multiple of the units to be cut, comprising a forming cutter movable to cut said material, means for driving said block forming mechanism to advance with said material toward said unit cutting mechanism, and means for automatically disconnecting said block forming mechanism from said driving means when advanced to a point adjacent said unit cutting mechanism.

6. In a machine of the class described, unit cutting mechanism operated to cut material advanced thereto into units of equal length, block forming mechanism arranged to form said material so advanced into a block equal in length to a multiple of the units to be cut, comprising a forming cutter movable to cut said material, means for driving said block forming mechanism to advance with said material toward said unit cutting mechanism,

- means for automatically disconnecting said block forming mechanism from said driving means when advanced to a point adjacent said unit cutting mechanism, and means for reconnecting said block forming mechanism to said driving means only when said forming cutter is at a distance from the cutting plane of the unit cutting mechanism equal to a multiple of the unit lengths.
10. 7. In a machine of the class described, unit cutting mechanism operated to cut material advanced thereto into units of equal length, block forming mechanism arranged to form said material so advanced into a block equal in length to a multiple of the units to be cut, comprising a forming cutter movable to cut said material, means for driving said block forming mechanism to advance with said material toward said unit cutting mechanism, means for automatically disconnecting said block forming mechanism from said driving means when advanced to a point adjacent said unit cutting mechanism, and means for reconnecting said block forming mechanism to said driving means only when said forming cutter is at a distance from the cutting plane of the unit cutting mechanism equal to a multiple of the unit lengths, said forming cutter being movable to cut said material only when said block forming mechanism is in a position for being connected to said driving means.
8. In a machine of the class described, unit cutting mechanism operated to cut material advanced thereto into units of equal length, block forming mechanism arranged to form said material so advanced into a block equal in length to a multiple of the units to be cut, comprising a forming cutter movable transversely of the block to cut said material, means permitting the operation of said forming cutter to cut said material only when said forming cutter is at a distance from the cutting plane of said unit cutting mechanism equal to a multiple of the unit lengths.
9. In a machine of the class described, unit cutting mechanism operated to cut material advanced thereto into units of equal length, a conveyor for advancing with material to said unit cutting mechanism, block forming mechanism arranged to form said material so advanced into a block equal in length to a multiple of the units to be cut, comprising a forming cutter movable to cut the material, and means for driving said block forming mechanism to advance with said material at the same rate of speed as said conveyor, said forming cutter serving as a pusher for an advancing block of material on said conveyor and as an abutment for locating the forward end of a succeeding block of material, means arranged for resetting said block forming mechanism at various distances from said unit cutting mechanism but permitting the connection of said block forming mechanism to its driving means only at a distance from the cutting plane of said unit cutting mechanism equal to a multiple of said unit lengths, said forming cutter being movable to cut the material on said conveyor only when said block forming mechanism is in a position to be connected to the driving means.
10. 10. In a machine of the class described, unit cutting mechanism operated to cut material advanced thereto into units of equal length, a conveyor for advancing with material to said unit cutting mechanism, block forming mechanism arranged to form said material so advanced into a block equal in length to a multiple of the units to be cut, comprising a forming cutter movable to cut the material, and means for driving said block forming mechanism to advance with said material at the same rate of speed as said conveyor, said forming cutter serving as a pusher for an advancing block of material on said conveyor, and as an abutment for locating the forward end of a succeeding block of material.
11. In a machine of the class described, unit cutting mechanism operated to cut material advanced thereto into units of equal length, a conveyor for advancing with material to said unit cutting mechanism, block forming mechanism arranged to form said material so advanced into a block equal in length to a multiple of the units to be cut, comprising a forming cutter movable to cut the material, means for driving said block forming mechanism to advance with said material at the same rate of speed as said conveyor, said forming cutter serving as a pusher for an advancing block of material on said conveyor and as an abutment for locating the forward end of a succeeding block of material, and means arranged for resetting said block forming mechanism at various distances from said unit cutting mechanism but permitting the connection of said block forming mechanism to its driving means only at a distance from the cutting plane of said unit cutting mechanism equal to a multiple of said unit lengths.
12. In a machine of the class described, unit cutting mechanism operated to cut material advanced thereto into units of equal length, a conveyor for advancing with material to said unit cutting mechanism, block forming mechanism arranged to form said material so advanced into a block equal in length to a multiple of the units to be cut, comprising a forming cutter movable to cut the material, means for driving said block forming mechanism to advance with said material at the same rate of speed as said conveyor, said forming cutter serving as a pusher for an advancing block of material on said conveyor and as an abutment for locating the forward end of a succeeding block of material, and means arranged for resetting said block forming mechanism at various distances from said unit cutting mechanism but permitting the connection of said block forming mechanism to its driving means only at a distance from the cutting plane of said unit cutting mechanism equal to a multiple of said unit lengths, said forming cutter being movable to cut the material on said conveyor only when said block forming mechanism is in a position to be connected to the driving means.
13. In a machine of the class described, unit cutting mechanism operated to cut material advanced thereto into units of equal length, a conveyor for advancing with material to said unit cutting mechanism, block forming mechanism arranged to form said material so advanced into a block equal in length to a multiple of the units to be cut, comprising a forming cutter movable to cut the material, and means for driving said block forming mechanism to advance with said material at the same rate of speed as said conveyor, said forming cutter serving as a pusher for an advancing block of material on said conveyor, and as an abutment for locating the forward end of a succeeding block of material.

length, block forming mechanism arranged to form said material so advanced into a block equal in length to a multiple of the units to be cut, comprising a forming cutter 5 movable to cut said material, means for driving said block forming mechanism to advance with said material toward said unit cutting mechanism, means operated by the cutting movement of said forming cutter to connect 10 said block forming mechanism to its driving means, said forming cutter being movable to cut said material only when at a distance from the cutting plane of said unit cutting mechanism equal to a multiple of the unit 15 lengths.

14. In a machine of the class described, unit cutting mechanism operated to cut material advanced thereto into units of equal length, block forming mechanism arranged to form said material so advanced into a block equal in length to a multiple of the units to be cut, comprising a forming cutter movable 20 to cut said material, means for driving said block forming mechanism to advance with said material toward said unit cutting mechanism, means automatically disconnecting said block forming mechanism from its driving means when said forming cutter reaches a point adjacent said unit cutting mechanism, means operated by the cutting movement of 25 said forming cutter to connect said block forming mechanism to its driving means, said forming cutter being movable to cut said material only when at a distance from the cutting plane of said unit cutting mechanism equal to a multiple of the unit 30 lengths.

15. In a machine of the class described, unit cutting mechanism comprising a movable cutter operated to cut material advanced 40 thereto into units of equal length, means for advancing material to said unit cutting mechanism by a continuous movement, and means to operate said unit cutting mechanism to cut said units at right angles to the axis of the material being advanced, comprising a carrier 45 for said movable cutter arranged to advance during said cutting operation at the same rate of speed as said advancing material and means to yieldingly embrace the sides 50 of the units being cut during the cutting operation.

16. In a machine of the class described, unit cutting mechanism comprising an oscillating cutter for cutting material advanced thereto into units of equal length, means for advancing material to said unit cutting mechanism, a reciprocating carrier for said cutter and means for advancing said carrier during said cutting operation at the same rate 55 of speed as said advancing material and means to yieldingly embrace the sides of the units being cut during the cutting operation.

17. In a machine of the class described, unit cutting mechanism operated to cut ma-

terial advanced thereto into units of equal 65 length, block forming mechanism arranged to form said material so advanced into a block equal in length to a multiple of the units to be cut, a driving screw for advancing said block forming mechanism toward said unit cutting mechanism, means for connecting said block forming mechanism with said driving screw comprising a nut member for engagement with said driving screw.

18. In a machine of the class described, unit cutting mechanism operated to cut material advanced thereto into units of equal length, block forming mechanism arranged to form said material so advanced into a block equal in length to a multiple of the units to be cut, comprising a forming cutter movable 70 to cut said material, a driving screw for advancing said block forming mechanism toward said unit cutting mechanism, means for connecting said block forming mechanism with said driving screw comprising a nut member, means operated by the movement of said forming cutter in cutting said material to engage said nut member with said driving screw, said screw being engageable 75 with said driving screw only when said forming cutter is at a distance from the cutting plane of said unit cutting mechanism equal to a multiple of said unit lengths for engagement with said driving screw.

19. In a machine of the class described, mechanism to cut a block of material into units of equal length, block forming mechanism arranged to form material into a block having a length equal to multiples of said 80 units and to feed the formed block to the unit cutting mechanism, and means for embracing the unit while it is being cut from said block adapted and arranged to separate it 85 from the block after the cutting operation.

20. In a machine of the class described, unit cutting mechanism for cutting successive units from a block of material while the block is being advanced, mechanism for advancing the block to the unit cutting mechanism and in unison therewith and for forming the material into a block having a length 90 equal to multiples of said units.

21. In a machine of the class described, unit cutting mechanism for cutting a block of material advanced thereto into units, a belt for advancing a block to said mechanism, a cutter movable towards and away from said belt for cutting a block thereon, a support for said cutter arranged to allow a cutting movement of said cutter only when it is located at distances from said unit cutting mechanism which are equal to multiples of the lengths 95 of the units to be cut.

In testimony whereof they have affixed 100 their signatures.

ELMER L. SMITH.
HORACE J. PAYNTER.
